UNITED STATES PATENT OFFICE.

ALBERT H. HOOK AND J. HENRY DARLINGTON, OF NEW YORK, N. Y.

IMPROVEMENT IN COATING BARRELS TO RENDER THEM OIL-TIGHT.

Specification forming part of Letters Patent No. 43,025, dated June 7, 1861.

To all whom it may concern:

Be it known that we, ALBERT H. HOOK and J. HENRY DARLINGTON, of the city, county, and State of New York, have invented certain new and useful improvements for coating barrels on the inside and stopping them, so as to render them proof against leakage when filled with oils of various kinds and like substances; and we do hereby declare and ascertain our said improvements as follows:

Heretofore many attempts have been made to guard against the loss of oils, &c., by evaporation when in barrels or like vessels of wood, but without success. For this purpose the inside of barrels have been coated with glue. This has, however, only partially remedied the difficulty. The glue cracks and leakage takes place whenever so carefully prepared, so that this and all other remedies heretofore adopted have failed. To remedy all former difficulties and render barrels or reservoirs of wood perfectly impervious to the attacks of oils, we have saturated the pores of the wood, as well as coated the surface thereof, with a compound of glue and molasses, such as is well known and used in the manufacture of printer's rollers. The barrel or other vessel to contain oil should be filled with the compound, (the exact proportions of which are not essential, so that there is molasses enough to prevent the cracking of the glue,) and it is forced into the pores of the wood by either of two well-known processes—hydraulic pressure or vacuum produced by ordinary apparatus for that purpose, which is too well known to require any description here. By this means the material is drawn or forced into the pores of the wood and renders it oil-proof, producing an elastic yield-

ing coat of impenetrable material against highly-rectified oils. In cases where there is water mixed with the oils, as in crude petroleum, we first saturate the barrel with glue, as above described, and then fill it with a solution of tannin, which so acts upon the glue as to enable it to repel the attack of the water combined with the oil. We have found by thus treating wooden barrels, &c., that they are impervious to oil, and guard them perfectly against leakage or evaporation in transporting and handling, as well as in storing, which has heretofore been a serious loss.

Gum-arabic and like substances may, in some instances, be used to saturate the pores of the wood, but we prefer the use of glue.

In order to render the barrel perfectly tight, we propose after it is filled to screw a metal bung into the bung-hole, which should be previously tapped for the purpose and well saturated with the compound before the insertion. To insure a perfect sealing of the joints around the head of the barrel on the inside, we give those parts a second coating after the first is set.

Having thus fully described our improvement in rendering barrels, &c., impervious to oil, &c., what we claim therein as new, and for which we desire Letters Patent, is—

1. Saturating wooden vessels, as and for the purposes hereinabove set forth.
2. In combination therewith the manner of stopping the bung-hole.

ALBERT H. HOOK.
J. H. DARLINGTON.
